MOTORCYCLE BODY UNIT

Charles H. Fehn, Thousand Oaks, Calif., assignor to Nethercult Industrial Corporation, Sylmar, Calif., a corporation of California

Filed Aug. 20, 1963, Ser. No. 76,290

Term of patent 14 years

(Cl. D90—8)

FIG. 1 is a perspective view of a motorcycle body unit embodying my new design;

FIG. 2 is a side elevational view of a side of the motorcycle opposite that shown in FIG. 1;

FIG. 3 is a fragmentary top plan view of the motorcycle; and

FIG. 4 is a rear elevational view thereof.

I claim:

The ornamental design for a motorcycle body unit, as shown.
